UNITED STATES PATENT OFFICE.

CECIL VERNON AUGENSTEIN, OF MACKSBURG, OHIO.

WIRE-LINE SOCKET.

Application filed March 22, 1921. Serial No. 454,410.

To all whom it may concern:

Be it known that I, CECIL V. AUGENSTEIN, a citizen of the United States, and a resident of Macksburg, in the county of Washington, State of Ohio, have invented certain new and useful Improvements in Wire-Line Sockets, of which the following is a specification.

This invention relates to an improvement 10 in wire line sockets for use with well drilling machinery or the like.

The object of the invention is to provide an improvement of this character which permits of the use of a wire line or rope and 15 obviates the necessity of using a "manila cable," the socket embodying spring means for providing the desired resiliency.

Another object is to provide an improvement 20 of this character which is extremely simple and durable in construction, reliable in operation and easy and inexpensive to manufacture.

Another object is to provide an improvement 25 of this character wherein there is provided cushioning means for relieving the elements of shock and jars.

Other objects and advantages of the invention reside in certain novel features of construction, combination and arrangement 30 of parts which will be hereinafter more fully described and particularly pointed out in the appended claim, reference being had to the accompanying drawings forming part of this specification, and in which:

35 Figure 1 is a view, in elevation, illustrating the preferred embodiment of the invention;

Figure 2 is a view thereof in transverse vertical section;

40 Figure 3 is a view in horizontal section, on line 3-3 of Figure 2; and

Figure 4 is a similar view, on line 4-4 of Figure 2.

Referring to the drawings wherein for the 45 sake of illustration is shown the preferred embodiment of the invention, the numeral 10 designates the cylindrical stock or body portion of the socket which is provided at its upper end with an integral head 11 from 50 which an externally threaded coupling con-

nection 12 extends. The lower end of the stock or body portion is open and is internally threaded for engagement with a coupling member 13 of a tool or the like.

Within the body portion 10 a coil spring 55 15 is arranged and abuts the head 11 at its upper end. The lower end of the spring abuts a follower 16 which is provided with an opening flaring as at 17, toward the lower end of the follower. A wire line or wire 60 rope is designated at W, and at its lower end it is spread or untwisted and is received in the flaring opening 17 of the follower 16 wherein it is secured to the follower by babbetting or the like, as indicated at 18. 65 Above the connection of the wire line or rope to the follower a tube 20 has threaded connection therewith, the tube 20 extending up through the body portion 10 and out through the head 11 and coupling member or connection 12. As shown in Figure 2 the tube 20 is arranged in encircling relation with respect to the wire line 10 and is arranged 70 within the coil spring 15.

A cushioning and protective disk 25 is 75 arranged in the body portion on top of the coupling member 13 so as to be interposed between the coupling member and the follower whereby it serves to take up the shocks and jars incident to the hammering action of 80 the follower and to relieve the coupling member and the socket of the deleterious strain incident thereto.

In operation, the spring 15 comes into play to give the wire line the desired resiliency since it is compressed by the follower 16 which moves upwardly into the cylindrical body portion when compressing the spring. When the follower descends it strikes the cushioning disk 25 which absorbs the shocks and then takes up the strains. All during this action the spring is effectively isolated from the wire line by means of the tube 20 which moves with the follower in order to perform this function. 95

As shown in Figure 1 the body portion 10 is provided adjacent its lower end with a squared portion 10^a and similarly the coupling member 13 is provided with a squared portion 13^a, these squared portions being 100

adapted to cooperate with an operating tool in the assembly and disassembly of the socket.

I claim:

- 5 A wire line socket comprising a body portion having a head at one end and having its other end open and internally threaded, a spring arranged in said body portion and abutting the head at one end, a follower op-

erating in said body portion and abutting 10 the other end of the spring and adapted for connection with the wire line cable, a coupling member having threaded engagement with the lower end of the body portion and a cushioning disk arranged between the 15 coupling member and the follower.

CECIL VERNON AUGENSTEIN.
